UNITED STATES PATENT OFFICE.

ALFRED C. FUNK, OF MOLINE, ILLINOIS, ASSIGNOR TO DEERE & COMPANY, OF MOLINE,
ILLINOIS, A CORPORATION OF ILLINOIS.

ELEVATOR-SUPPORT FOR HARVESTERS.

1,121,620.

Specification of Letters Patent. Patented Dec. 22, 1914.

Application filed February 23, 1912. Serial No. 679,324.

To all whom it may concern:

Be it known that I, ALFRED C. FUNK, citizen of the United States, residing at Moline, in the county of Rock Island and 5 State of Illinois, have invented certain new and useful Improvements in Elevator-Supports for Harvesters, of which the following is a specification, reference being had therein to the accompanying drawing.

10 My invention relates to improvements in harvester-binders in which the rear of the upper elevator is supported from the seat-bar; and the object of my invention is to provide a support which can be readily adjusted to preserve the proper relation of the 15 upper with the lower elevator necessary for a proper conveyance of the grain to the binder.

Referring to the accompanying drawings 20 in which similar numerals indicate identical parts Figure 1 is a rear perspective view showing as much of a harvester-binder as is necessary to illustrate the application of my improvement thereto. Fig. 2 is an enlarged 25 section on the line $x-x$ of Fig. 1; Figs. 3 and 4 are enlarged details.

The seat-bar 1 is preferably of the usual U-shaped type common to modern harvesters, and is secured to the front and rear of 30 the harvester-frame 2 in a well known manner. The lower elevator-frame 3 is rigid as usual, but the upper elevator frame 4 is of the floating type, and while it is supported rigidly at the front of the machine the rear 35 is only supported by a connection with the seat-bar, permitting flexibility and at the same time allowing sufficient distance between the rear of the elevator-frames for a proper conveyance of the grain to the 40 binder-deck; this distance between the rear of the elevator-frames generally becomes reduced, after continuous use of the machine, by sagging of the upper-elevator frame. To preserve the proper distance of the rear of 45 the upper-elevator frame 4 from the elevator-frame 3 I provide a member 5 rigidly secured to the seat-beam 1 and having divergent arms 6 and 7 projecting therefrom, and preferably integral therewith. The 50 lower arm 7 projects downwardly and has an enlarged end 8 which is a slot 9 practically parallel with the inclination of the elevator-frames; a bolt 10 passes through the rear side of the elevator-frame 4 and the 55 slot 9 and is secured by a nut to clamp the

arm 7 rigidly against the elevator-frame 4. The upper arm 6 projects stubbleward, its end 11 being flattened and preferably rectangular in form; centrally of the end 11 is a rectangular opening 12 having, parallel 60 with the top and bottom sides thereof, a series of serrations 13 approximately as long as the side of the opening 12; similar serrations 14 are formed on the end 11 between the opening 12 and the sides of the end 11 65 and at right angles to the serrations 13. A washer 15 is provided on its face with serrations 16 and 17 similar to the serrations 13 and 14 adapted to engage therewith, being held in place by a bolt 10^a which passes 70 therethrough and through the opening 12 and the elevator-frame 4. The elevator-frame 4 has a pivotal as well as a longitudinal movement on the bolt 10, and on the bolt 10^a the range of adjustment is limited 75 only by the size of the opening 12. In adjusting the elevator-frame 4 the nuts on the bolts 10 and 10^a are loosened, the elevator-frame 4 is then raised or lowered as desired; the nut on the bolt 10 is then tightened sufficient to hold the adjustment on the bolt 10, the washer 15 is then moved on the bolt 10^a until the serrations 16 and 17 thereon engage with the serrations 13 and 14 on the 80 end 11, the nut on the bolt 10^a is then tightened and the elevator-frame 4 is secure in 85 its new adjustment.

Having thus described my invention, what I claim is—

1. In a harvester-binder, the combination 90 of an upper and a lower elevator-frame, a seat-bar, a member secured to the seat-bar, means to support the upper elevator-frame at more than one point on said member, and means to adjust the upper elevator-frame at 95 each point of support on the supporting member, the adjustment at one of the supporting points being in a straight line and transversely thereof.

2. In a harvester-binder, the combination 100 of an upper and a lower elevator-frame, a seat-bar, a member secured to the seat-bar and having divergent arms on which the upper elevator-frame is supported, and means to adjust the upper elevator-frame on said 105 arms, the adjustment on one of the arms being in a straight line and transversely thereof.

3. In a harvester-binder, the combination 110 of an upper and a lower elevator-frame, a

seat-bar, a member secured to the seat-bar and having two diverging arms upon which the upper elevator-frame is supported, and means to adjust the upper elevator-frame on said arms, the adjustment on one of the arms being in a straight line and transversely thereof.

4. In a harvester-binder, the combination of an upper and a lower elevator-frame, a seat-bar, a member secured to the seat-bar and having upper and lower diverging arms upon which the upper elevator-frame is supported, and means to adjust the upper elevator-frame on said arms, the adjustment being in a straight line and transversely thereof.

5. In a harvester-binder, the combination of an upper and a lower elevator frame, a seat-bar, a member secured to said seat-bar and having an upper and a lower arm upon which the upper elevator-frame is adjustably supported, the adjustment on the lower arm being in a straight line only, and the

adjustment on the upper arm being in a straight line and transversely thereof.

25

6. In a harvester-binder, the combination of an upper and a lower elevator-frame, a seat-bar, a member secured to the seat-bar and having upper and lower diverging arms, means to adjustably secure the upper elevator-frame to the lower arm, an enlarged opening in the upper arm, a bolt attached to the upper elevator-frame and laterally movable in said opening, and a washer on said bolt having serrations extending in two directions to engage with similar serrations on the upper arm, and adapted to be secured in such engagement when the upper elevator-frame is adjusted.

Correction in Letters Patent No. 1,121,620.

It is hereby certified that in Letters Patent No. 1,121,620, granted December 22, 1914, upon the application of Alfred C. Funk, of Moline, Illinois, for an improvement in "Elevator-Supports for Harvesters," an error appears in the printed specification requiring correction as follows: Page 1, line 51, after the reference-numeral "8" insert the word *in*; and that the said Letters Patent should be read with this correction therein that the same may conform to the record of the case in the Patent Office.

Signed and sealed this 19th day of January, A. D., 1915.

[SEAL.]

R. F. WHITEHEAD,

Acting Commissioner of Patents.
